[57] CLAIM

The ornamental design for a support bracket for clothes closet rod, as shown and described.

DESCRIPTION

FIG. 1 is a left side, top and front perspective view of a support bracket for clothes closet rod showing my new design;

FIG. 2 is a front elevational view thereof;

FIG. 3 is a right side elevational view thereof, the opposite side being a mirror image;

FIG. 4 is a rear elevational view thereof; and

FIGS. 5 & 6 are respectively top and bottom plan views thereof.
